(57) **CLAIM**

(51) **LOC (8) Cl. 28-03**

The ornamental design for a stand for an electrical appli-
ance, as shown and described.

(52) **U.S. Cl. D28/38; D28/73; D26/94**

DESCRIPTION

(58) **Field of Classification Search D28/38,**

FIG. 1 is a perspective view showing the front side and
upper portion of a stand for an electrical appliance accord-
ing to the present invention; and,

D28/73; D26/94; 206/581, 823, 373; 248/117.2–117,

FIG. 2 is a perspective view showing a rear surface, opposite
side and bottom of a stand for an electrical appliance in
accordance with the present invention.

248/176.2; 219/222, 242; 211/70.6; D9/669

The broken lines are shown for illustrative purposes only
and form no part of the claimed design.

See application file for complete search history.
